UNITED STATES PATENT OFFICE.

JOHN JOSEPH BRADSHAW, OF JERSEY CITY, NEW JERSEY.

LIFTING-JACK.

No. 853,437.

Specification of Letters Patent.

Patented May 14, 1907.

Application filed June 23, 1906. Serial No. 323,063.

To all whom it may concern:

Be it known that I, JOHN JOSEPH BRADSHAW, a citizen of the United States, residing at Jersey City, in the county of Hudson and State of New Jersey, have invented a new and useful Improvement in Lifting-Jacks, of which the following is a specification.

This invention relates to lifting jacks and more particularly to pulling lifting jacks adapted to be used for replacing cars on tracks, the object being to provide a jack so constructed that the object being lifted can be pulled toward the jack at the same time.

With this object in view, the invention consists in the novel features of construction, combination and arrangement of parts, hereinafter fully described and pointed out in the claims.

In the drawing forming a part of this specification:—Figure 1 is a perspective view of my improved lifting jack. Fig. 2 is a longitudinal sectional view showing the bar partly broken away. Fig. 3 is a transverse sectional view. Fig. 4 is a top plan view of the jack with the lifting bar removed.

In the drawings A indicates a block having upwardly projecting sides A', provided with journal bearings B secured on the top on which the reduced rounded ends C', of the square shaft C is mounted. Secured centrally on the shaft C is a gear wheel D, having ratchet wheels E secured on the shaft to each side of the gear wheel, which are adapted to be engaged by pawls F', mounted on a shaft F, between the sides adjacent its forward end, which prevents the same from turning forward. Mounted on the reduced ends C', of the shaft C, to each side of the ratchet wheels E, are arms G extending rearwardly and connected together at their ends by a bar H, having a rounded upper face for the purpose hereinafter described.

A bar I is secured between the arms G provided with pawls I', adapted to engage the ratchet wheels E. A lever bar J, having a toothed portion J', is adapted to be mounted on the gear wheel D, provided with a curved end J², and a socket J³, in its other end in which is mounted a lever bar K, of any length desired. The block A is provided with V-shaped feet A², extending across the rear, at each end which prevents the block from slipping when the lever is pushed downwardly.

From the foregoing description it will be readily seen that when the bar is pressed down, so as to engage the curved surface of

the cross bar H, the pawls I', will engage the ratchet wheels E and revolve the gear wheel D causing the bar to be drawn rearwardly carrying with it, the object being lifted which will be held in that position by the pawls F'.

Having thus fully described my invention, what I claim as new and desire to secure by Letters Patent is:—

1. In a lifting jack, the combination with a shaft carrying a gear wheel, of arms mounted on said shaft a toothed lever bar mounted on said gear wheel adapted to engage said arms and means carried by said arms for rotating said shaft for the purpose described. 70

2. In a lifting jack, the combination with a shaft mounted in journals carrying a gear wheel, of arms pivotally mounted on said shaft, a toothed lever bar mounted on said gear wheel adapted to engage said arms, the teeth of the bar meshing with said gear, and means carried by the arms for rotating said gear for the purpose described. 75

3. In a lifting jack, the combination with a block having a shaft mounted therein, carrying a gear wheel or ratchet wheel, a tooth bar mounted on said gear wheel and arms mounted on said shaft provided with pawls adapted to engage said ratchet wheel and rotate said gear-wheel when engaged by said bar, for 85 the purpose described. 8c

4. In a lifting jack, the combination with a block, of a shaft mounted in said block provided with a gear and ratchet wheels, arms mounted on said shaft connected together 90 by a cross bar, pawls carried by said arms and a toothed bar mounted on said gear wheel, adapted to engage the cross bar of the arms, for the purpose described.

5. In a lifting jack, the combination with a block carrying a gear and ratchet wheel, arms provided with pawls adapted to engage said ratchet wheel, and a toothed bar mounted on said gear wheel adapted to engage said arms, for the purpose described. 95 100

6. In a lifting jack, the combination with a block provided with upwardly projecting sides, of a shaft mounted between said sides, a gear wheel secured on said shaft, ratchet wheels fixed on said shaft, arms provided with pawls, mounted on said shaft, connected together by a cross bar, a toothed bar mounted on said gear wheel adapted to engage said cross bar, and pawls carried by said bar adapted to engage said ratchet 105 wheels, for the purpose described. 110

7. In a lifting jack, the combination with a

block, a gear and ratchet wheels mounted in said block, arms pivotally mounted in said block carrying pawls and a toothed lever bar mounted on said gear adapted to engage said arm, for the purpose described.

8. In a lifting jack, the combination with a block, of a shaft mounted on said block carrying gear and ratchet-wheels, arms mounted on said shaft carrying pawls adapted to engage said ratchet-wheels and a toothed lever bar mounted on said gear wheel, adapted to engage said arms, for the purpose described.

9. In a lifting jack, the combination with a block, provided with upwardly projecting

sides, of a shaft mounted between said sides, a gear wheel secured on said shaft, ratchet wheels fixed on said shaft to each side of said gear wheel, arms mounted on said shaft connected together at their ends by a cross-bar, 20 pawls carried by said arms, a shaft mounted between the side of the block, carrying pawls adapted to engage said ratchet-wheels and a toothed lever bar mounted on said gear adapted to engage the cross-bar of the arms, 25 for the purpose described.

JOHN JOSEPH BRADSHAW.
